UNITED STATES PATENT OFFICE.

CHARLES A. FOX, OF NEW YORK, N. Y.

COLLAPSIBLE BOX.

Application filed November 1, 1924. Serial No. 747,147.

To all whom it may concern:

Be it known that I, CHARLES A. FOX, a citizen of the United States, residing at New York city, county of New York, and 5 State of New York, have invented certain new and useful Improvements in Collapsible Boxes, of which the following is a specification.

This invention relates to improvements in 10 receptacles, and has particular reference to a collapsible box similar to the type disclosed in my co-pending application, Serial No. 745,273, filed October 23, 1924.

An object of the present invention is to 15 provide an improved box of simple and inexpensive construction wherein certain of the walls of one section of the box are reinforced when the box is in operative position by overlapping and interlocking a portion 20 of an inner lining for said section with each of said walls.

Another object is to form a locking tongue in a portion of one wall of an inner reinforcing lining for a section of the box, 25 which tongue may be overlapped with an end of an adjacent wall of said section and then engaged with the latter wall to lock the lining in its reinforcing position.

The above and other objects will appear 30 more clearly from the following detailed description when taken in connection with the accompanying drawings, which illustrate a preferred embodiment of the inventive idea.

35 In the drawings—

Figure 1 is a perspective view of a collapsible box constructed in accordance with the invention, the box being shown open;

Figure 2 is a vertical longitudinal section 40 through the box;

Figure 3 is a plan view of the box partially folded;

Figure 4 is a perspective view of one 45 corner of the box, showing the improved means for attaching the lining to a side wall of a section of the box; and

Figure 5 is a fragmentary top plan view, partly in section.

The present invention is shown in connection 50 with a box commonly known as the telescoping type, but it is to be expressly understood that the drawings are used merely for the purpose of illustrating the invention as a whole and not to define the limits thereof, reference being had to the appended claims for this purpose.

The box proper is preferably formed from a single sheet of suitable material, such as cardboard or the like, and which is cut to provide the bottom and top sections 6 60 and 7, respectively, joined by an intermediate section 8, which forms the outer rear wall of the box when the same is in closed position.

The bottom section 6 includes the front 65 wall 9 and side walls 10, the front ends of which are overlapped with the ends of the front wall secured thereto by fasteners 11. The invention further provides an inner lining for the bottom section, generally indicated by the numeral 12, and formed from a single length of material, the extremities of which are overlapped with the ends of the front wall 9 upon the inner surface thereof and likewise secured to the front wall by 70 means of the fasteners 11. The lining is bent to provide the side walls 13 and intermediate wall 14, the latter of which forms the rear wall of the bottom section 6 when the lining is in extended position. The bottom edge of the intermediate wall 14 is provided with a flange 15 which engages the bottom of the section to lend rigidity to the wall 14 so as to prevent the inward collapsing 75 of said wall when the box is set up. Intermediate the ends of the side walls 13 of the lining the same is scored, as indicated at 16, so that the lining may be collapsed or folded to the position shown in Figure 3 80 when not in use.

Each of the side walls 13 of the lining are cut out intermediate the top and bottom edges thereof and at the point of junction thereof with the intermediate wall 14 to provide a forwardly extending locking 85 tongue 17 having a notch 18 adjacent its free end to form a tab 19 for a purpose which will presently appear. When the lining 12 is being adjusted to its operative position the tongue 17 is extended around 100 and overlapped with the rear end of the adjacent side wall 10 so that said rear end is interposed between the portion of the lining extending interiorly of said wall and the tongue 17. The side wall 10 is provided with a longitudinally extending slot 20 into which the tab 19 is then inserted so as to lock the tongue 17 in position and thus maintain the lining 12 in its extended and reinforcing position with respect to the side 110 walls of the bottom section.

The top section 7 is scored, as indicated at

21, to permit of the side walls 22 thereof being collapsed and the front wall 23 folded thereupon and the material of said side walls is further provided with a fold 24 adjacent 5 the intermediate section 8, which also permits of folding the top section when it is desired to collapse the box.

What is claimed is:

- 10 1. In a collapsible box, a section including side walls, an inner lining for said section also including side walls, and a locking tongue for each of the latter side walls joined to its wall adjacent one end thereof, and capable of being extended around an 15 end of an adjacent side wall of said section to engage said end between said tongue and adjacent portion of the lining to retain the latter in operative position.
- 20 2. In a collapsible box, a section including side walls, an inner lining for said section also including side walls, and a locking tongue for each of the latter side walls joined to its wall adjacent one end thereof, and capable of being extended around an 25 end of an adjacent side wall of said section

to engage said end between said tongue and adjacent portion of the lining to retain the latter in operative position, said locking tongue having a portion projecting through the side wall of the section to retain the 30 tongue in engagement with said side wall.

3. In a collapsible box, a section including side walls, a lining therefor also including side walls and an intermediate wall forming the rear wall of said section, and a 35 locking tongue cut from each of the side walls of said lining with its inner end extending coincident with the line of connection between said wall and said intermediate wall, said tongue being capable of receiving the adjacent end of a side wall of said section between the same and the remaining portion of the side wall of said lining from which said tongue is cut, and the free end of said tongue being inserted through said 40 side wall of the section to retain the lining in operative position.

In testimony whereof I have affixed my signature.

CHAS. A. FOX.
